PEDESTAL TABLE

John B. Thorn, Lynchburg, and Andre Bus, Altavista, Va., assignors to The Lane Company Inc., Altavista, Va., a corporation of Virginia

Filed Apr. 10, 1967, Ser. No. 6,610

Term of patent 14 years

(Cl. D33—14)

Fig. 1.

Fig. 2.

Fig. 3.

FIGURE 1 is a side elevation elevation view of the pedestal table of our new design; an elevation view from each of the other three sides of the table would be substantially the same in appearance;

The ornamental design for a pedestal table, as shown and described.
